V. PETRACEK

Des. 166,210

WOVEN PLASTIC FABRIC

Filed Oct. 17, 1951

INVENTOR,
VACLAV PETRACEK,

BY ATTORNEY

UNITED STATES PATENT OFFICE

166,210

WOVEN PLASTIC FABRIC

Vaclav Petracek, Long Island City, N. Y., assignor
to Hafner Associates, Inc., New York, N. Y.

Application October 17, 1951, Serial No. 16,997

Term of patent 3½ years

(Cl. D87—3)

To all whom it may concern:

Be it known that I, Vaclav Petracek, a citizen of no country, residing in Long Island City, County of Queens, and State of New York, have invented a new, original, and ornamental Design for a Woven Plastic Fabric, of which the following is a specification, reference being had to the accompanying drawing, forming part thereof, wherein, the figure on the drawing is a plan view of a woven plastic fabric showing my new design.

I claim:

The ornamental design for a woven plastic fabric, substantially as shown.

VACLAV PETRACEK.
